UNITED STATES PATENT OFFICE.

SETH WHEELER, OF ALBANY, NEW YORK.

BOSOM-PAD.

SPECIFICATION forming part of Letters Patent No. 404,881, dated June 11, 1889.

Application filed March 7, 1888. Serial No. 266,438. (No model.)

To all whom it may concern:

Be it known that I, SETH WHEELER, a citizen of the United States, residing at Albany, in the county of Albany and State of New York, have invented new and useful Improvements in Bosom Pads or Forms, of which the following is a specification.

My invention relates to improvements in bosom pads or forms; and it has for its object to provide a simple, cheap, light, and strong form which will be yielding and elastic when subjected to pressure.

In the ordinary practice dress-forms are made of permanent materials—as metal, rubber, fabrics held in shape by stiffening ribs or frames, &c.—and these, besides being liable to heat the body of the wearer, are affected by perspiration, and cannot, on account of their cost, be thrown aside and replaced by new ones.

It is my object, further, therefore, to provide a form which will have the necessary elasticity and strength, and which, besides being thoroughly ventilated, may when soiled or injured in any way be thrown aside and replaced by a new one.

With these objects in view the invention consists in a bosom-pad formed of a single unseamed piece of fabric, substantially as hereinafter described, said fabric being corrugated and perforated and capable of retaining its shape (or regaining it after being distorted) without the aid of supplemental stiffening means.

The invention is more fully described hereinafter in connection with the accompanying drawings, wherein—

Figure 1 is a front view of a form having radial corrugations. Fig. 2 is a side view thereof. Fig. 3 is a front view of a form having spiral corrugations. Fig. 4 is a similar view of a form having concentric corrugations.

Referring by letter to the drawings, the forms may be of any desired shape; but they are preferably rounded or semi-spherical, as shown in the drawings, and they are formed of a single piece of paper, stiffened linen, or

cloth-covered paper stamped or blocked into the desired shape. 50

The corrugations consist of the ribs A and the intervening grooves B, and they may be either radial, as in Fig. 1, or spiral, as in Fig. 3, or concentric, as in Fig. 4. The object and advantage of these corrugations are that they 55 add materially to the strength of the form, and at the same time allow it to yield without cracking or creasing the surface. Upon being released from pressure the form provided with corrugations immediately regains its 60 original shape.

These forms may be further provided with perforations in their sides, as seen at C, thus allowing a free circulation of air in their interior and preventing a heating of the body 65 of the wearer. In practice the perforations should be provided in the ridges of the corrugations and not in the furrows. The forms are light, thereby obviating the chafing which usually attends the use of heavy unyielding 70 forms.

It will be understood that the arches which comprise the surface of these forms strengthen the same and enable them to resist pressure. This corrugated form may be applied to other 75 materials besides paper and the other materials above referred to with advantage.

It will be observed by reference to the several forms of bosom-pads, as shown, that the salient feature resides in corrugating the pad 80 in lines throughout the entire body of the pad.

Having thus described my invention, what I claim, and desire to secure by Letters Patent of the United States, is—

As a new article of manufacture, a bosom-pad formed of a single unseamed piece of fabric corrugated and perforated, substantially as described.

In testimony that I claim the foregoing as 90 my own I have hereto affixed my signature in presence of two witnesses.

SETH WHEELER.
